HONING TOOL

Kirke W. Connor, Detroit, Mich., assignor to
 Micromatic Hone Corporation, Detroit, Mich.,
 a corporation of Michigan

Application January 8, 1934, Serial No. 705,664

7 Claims. (Cl. 51—184.2)

My invention relates to honing tools and particularly to a tool of the service type embodying free floating abrading elements having wide expansion.

5 While honing tools of the service type have been constructed and employed heretofore, the tools have proven more or less unsatisfactory for various reasons, primarily because of the chattering of the tool in the cylinders. Tools of this type 10 are usually of the off-center construction to have the pins of the abrading element extending beyond the tool center to provide the material expansion required in the tool. A service tool is one employed in garages for servicing all types 15 of engine blocks and, therefore, requires a large range of expansion to meet the various sizes of cylinders employed in different automobile engines.

In the present invention, I have provided a 20 service tool which is exceedingly rugged in construction and which provides the required expansion necessary for such tools. The possibility of chatter occurring between the tool and the surface of the cylinder wall during the grinding operation has been entirely eliminated, primarily by having the elements for adjusting the 25 abrading elements radially float freely independent of the means for supporting and driving the abrading elements in rotation. By this construction, I am able to employ more of the abrading 30 elements in the tool, in the small size four being operated, while in the larger size, as illustrated, six of the abrading elements may be utilized thereby increasing the abrading action and accelerating the abrading operation, while distributing the wear on the stones more evenly there-over.

Accordingly, the main objects of my invention are; to provide a honing tool having abrading 40 elements which are free to shift and tilt longitudinally; to provide an abrading tool wherein the abrading elements are driven by a portion of the tool in rotation independent of the radial adjusting elements which are free floating; to provide a honing tool having an adjustable head embodying a spring which applies a predetermined bias to the abrading elements to feed them radially during the honing operation; to incorporate stop means in the spring to retain the head 45 in adjusted position; and, in general, to provide a honing tool which is rugged, positive in operation and economical of manufacture.

Other objects and features of novelty of my invention will be either specifically pointed out 50 or will become apparent when referring, for a

better understanding of my invention, to the following description taken in conjunction with the accompanying drawing, wherein:

Figure 1 is a plan view, partly in section, of a honing tool embodying features of my invention, 5

Fig. 2 is a sectional view of the structure illustrated in Fig. 1, taken on the line 2—2 thereof,

Fig. 3 is a sectional view of the structure illustrated in Fig. 2, taken on the line 3—3 thereof,

Fig. 4 is a view in elevation of the spring employed in the honing tool illustrated in Fig. 1, 10

Fig. 5 is a top plan view of the structure illustrated in Fig. 4, and

Fig. 6 is a bottom plan view of the structure 15 illustrated in Fig. 4.

Referring to Fig. 1, the honing tool is built on a rigid spindle 10 which may be round, square, octagon or other shape. Preferably I employ shapes other than round or cylindrical to prevent the rotation of certain parts of the tool and I 20 have herein illustrated a hexagon shaped spindle to provide strength, clearance for the radial adjusting elements and to provide surfaces on which certain elements will not rotate.

Upon the upper end of the spindle an adjusting body 11 is provided while on the lower end thereof an abrading head 12 is disposed. The abrading head is constructed of a plurality of abrading shoes 13 having a medial slot 14 therein which is engaged by a positioning element 15 30 which is fixed against longitudinal and rotational movement on the spindle 10 by suitable means herein illustrated as a key 16.

A pair of oppositely disposed spiders 17 are mounted for longitudinal movement on the 35 spindle 10 but are retained thereon against rotation preferably by having a hexagon aperture, the walls of which closely fit about the spindle 10. The spiders 17 are provided with a plurality of slots 18 for receiving the shoes 13 and for 40 driving them in rotation. The bottom of the slot is sloped, as at 19 as illustrated in Fig. 1, for providing clearance to sloping surfaces 21 on each end of the shoes 13.

Each of the spiders 17 has adjustably retained 45 thereon washers 22 the outer peripheral edges 23 of which are sloped to mate with the sloping surface 21 provided on the ends of the shoes 13. The central portion of the washer 22 is provided with an aperture 24 which is larger than the spindle 10 to permit a lateral movement of the washer relative to the spindle. The washers are employed to adjust the shoes 13 radially when the spiders 17 are moved longitudinally of the tool. The shoes 13 tilt about the positioning ele- 50

ment 15 to provide free floating movement to the abrading head 12 independent of the driving means therefor. Spiders 25 are employed to co-operate with the spiders 17 for retaining the washers 22 related to the spiders 17 by having the two sets of spiders 17 and 25 riveted together in a predetermined manner.

The spiders 25 are provided with a plurality of extending lugs 26 which project outwardly of the washers 22 and are extended to engage the spiders 17. The spiders 17 and 25 at the lower end of the tool are retained in fixed relation by pins 27 having a shoulder 28 near each end thereof. The shoulder 28 near the lower end of the pin abuts against the top surface of the spider 17, the pin extending through both of the spiders and being peened over at the end to secure the spiders in fixed relation. I have illustrated in the figure three of the pins 27 employed on the tool. It is to be understood, however, that more or less of the pins may be utilized.

At the top of the abrading head 12, the spiders 17 and 25 are riveted together by hollow rivets 29 through which the pins 27 are slideable. In this manner the spiders 17 and 25 are retained in permanent fixed relation as a unit having the central portion spaced apart to receive the washers 22 which are slideable laterally therebetween.

The sides of the slots 14 in the shoes 13 may be sloped to provide clearance to permit the tools to tilt and at the same time prevent longitudinal movement of the shoes 13 relative to the positioning element 15. The shoes are provided with a channel 32 in which abrading sticks 33 are retained. The sticks comprise an abrading stone 34 mounted in a metal backing element 35 having projecting hook ends 36. The ends 36 receive garter springs 37 for retaining the abrading sticks 33 in the channel 32 of the shoes 13 and the shoes pressed against the surfaces 23 of the washers 22.

The upper ends of the pins 27 are provided with the shoulders 28 which abut against the lower surface of a nut 38 having a portion extending therethrough and riveted to the opposite side, at 39. In this manner, the nut 38 and the lower set of spiders 17 and 25 are held as a unit by the pins 27 and co-operate with the adjusting body 11 to effect the relative opposite movement of the upper and lower set of spiders for adjusting the shoes 13 radially of the spindle 10.

The adjusting body 11 includes an adjusting sleeve 41 comprising a handhold portion 42 and a threaded portion 43, the latter of which engages the threads of the nut 38, as illustrated in Fig. 1. The lower portion of the sleeve 41 is recessed to receive a spring 44 which engages the spider 25 at the top of the abrading head 12 for applying a downward bias thereto. The sleeve 41 is retained on the spindle by the tool supporting and driving connection 45 which is retained against rotation by a pin 46. A bayonet slot 47 is provided in the element 45 by which connection is made to a spindle which operates the tool.

A pin 48 is secured in the sleeve 41 for engaging one of a plurality of apertures 49 provided in one end of the spring 44. This pin retains the spring 44 fixed to the sleeve to rotate therewith. A plurality of apertures 51 are provided on the lower end of the spring which are successively engaged by a spring pressed ball 52 mounted in the top spider 25, as the spring is turned. Any adjustment set off by the turning of the sleeve 41 is retained fixed through the engagement of the spring pressed ball with one of the apertures 51 of the spring.

As illustrated in Figs. 4, 5 and 6, the spring is of a peculiar type, being from a hollow cylinder having offset slots 53 therein for the purpose of providing a predetermined tension per unit deflection and to have the deflection and tension follow a straight line curve or be in direct proportion at the initial loading and at the final expansion of the spring. Such a spring may be employed to retain the adjusting body 11 in adjusted position. This is affected by the engagement of the pin 48 with an aperture in the end of the spring to cause the spring to rotate with the sleeve 41 and through the engagement of the spring pressed ball 52 and an aperture 51 provided in the opposite end of the spring.

A guiding plate 54 is retained on the end of the spindle 10 by a bolt 55 and is provided with tapered sides 56. The plate is employed to guide and aid in inserting the tool into a cylinder and to protect the abrading head 12 against damage.

When a cylinder is to be honed, the tool may be inserted into the cylinder when the abrading head 12 is in retracted position. The turning of the adjusting sleeve 41 by grasping the handhold portions 42 draws the nut 38 upwardly while a bias is applied downwardly by the spring 44 to the upper spiders 17 and 25 to cause the upward movement of the lower spiders 17 and 25 and the downward movement of the upper spiders 17 and 25. This movement projects the shoes 13 outwardly to cause the abrading stones 34 to contact with the cylinder wall.

Further adjustment applies a bias between the upper and lower sets of spiders through the compression of the spring 44 to urge them toward each other and in this manner the tool is retained fixed in the cylinder and is expanded during the machining operation. A suitable driving device is secured to the bayonet connection 45 by which the tool is operated in rotation and is so disposed as to be reciprocated at the same time. During the grinding operation the shoes 13 are permitted to tilt about the positioning element 15 in view of the lateral shift permitted to the washer 22 which engages the sloping surfaces 21 of the shoes. Through the adjustment of the shoes in this manner more pressure and abrading is effected on the cylinder walls at points out of round, or tapered, and in this manner the out of round portions are machined away more rapidly so that at the end of the operation a true cylindrical wall is produced.

While I have described and illustrated but a single embodiment of my invention, it will be apparent to those skilled in the art that various changes, omissions, additions and substitutions may be made therein without departing from the spirit and scope of my invention as set forth in the accompanying claims.

I claim as my invention:

1. A honing tool including, in combination, a spindle, spiders mounted on said spindle for movement to and away from each other, abrading elements carried by said spiders for rotating said elements therewith, and means movable laterally of said spiders for effecting the radial movement of the abrading elements when the spiders are relatively moved toward and away from each other, and means for relatively moving said spiders.

2. A honing tool including, in combination, a spindle, longitudinally movable spiders on said spindle, washers carried by said spiders and movable laterally of the spindle, abrading elements carried by said spiders and engaging said wash-

ers, whereby the spiders effect the rotation of the abrading elements and the washers effect their radial movement independent of spiders.

5 3. A honing tool including, in combination, an abrading head, an adjusting body therefor for effecting the radial expansion of said head, a spring interposed between said adjusting body and said abrading head, and securing means engaging said spring for retaining the head in ad- 10 justed position.

10 4. A honing tool including, in combination, a spindle, an abrading head thereon comprising a plurality of abrading elements, means for effecting the rotation of said elements, means laterally movable independent of the rotating portion of said head, for effecting the expansion of said elements, adjusting means for positioning said expansion means, a spring rotatable with said adjusting means, and means carried by said head in engagement with said spring 15 for securing it in adjusted position.

15 5. A honing tool including, in combination, an abrading head, an adjusting body for expand- 20

ing the abrading head, a spring interposed between said head and body and fixed to said body, and means engaging said spring to retain the head and body against relative movement.

5 6. A honing tool including, in combination, an abrading end, an adjusting end for expanding the abrading end, a spring interposed between said ends and rotatable with one of said ends, and means engaging said spring to retain said ends against relative movement.

10 7. A honing tool including, in combination, a spindle, a pair of relatively movable spaced spiders carried by said spindle, a laterally movable washer carried by each spider, abrading elements engageable by said washers and spiders to be rotated through the engagement with said spiders and to be adjusted radially through the engagement with said washers when said spiders are relatively moved toward and away 15 from each other, and means for relatively mov- 20 ing the spiders.
